FIG. 12.

UNITED STATES PATENT OFFICE.

THOMAS J. DIXON, OF MADISON, WISCONSIN.

TUBE EXPANDER.

1,412,277.

Specification of Letters Patent. Patented Apr. 11, 1922.

Application filed July 23, 1920. Serial No. 398,463.

To all whom it may concern:

Be it known that I, THOMAS J. DIXON, a citizen of the United States, residing at Madison, in the county of Dane and State 5 of Wisconsin, have invented certain new and useful Improvements in Tube Expanders, of which the following is a specification.

My present invention, which has reference, generally, to tube expanders more specifically relates to improvements in that 10 type of tube expanders disclosed in my Patent No. 1,269,688, dated June 18, 1918.

My present invention primarily has for its purpose to provide an improved means of 15 the general character stated, in which the parts are more especially designed for bending or flaring the tube end outside the tube sheet at the same time that the tube is being expanded in the tube sheet and capable of 20 being so manipulated whereby the usual or extra process of bending or flaring the end of the tube with a hammer or like implement, after it has been expanded, preparatory to bending the tube, is eliminated.

With other objects in view that will hereinafter be brought out, my invention comprehends an implement or tool of the character and purposes stated, of a relative simple and inexpensive construction and which 30 embodies the peculiar features and novel arrangement of parts, all of which will be fully mentioned in the following detailed description, be specifically pointed out in the appended claim and are illustrated in the 35 accompanying drawings, in which:

Figure 1 is a perspective view of my new and improved construction of tool or implement for flaring and expanding boiler tubes and it illustrates a preferred form of my 40 invention.

Figure 2 is a perspective view of my improved tube flaring and expanding tool, the mandrel being omitted.

Figure 3 is a detail longitudinal section 45 of a portion of the tool and illustrates the operative relation of one of the expanding rollers and a cooperating flaring roller or disk.

Figure 4 is a transverse section of my improved construction of tube expanding and 50 flaring tool taken substantially on the line 4-4 on Figure 2.

Figure 5 is a longitudinal section of one of the expander rollers that works independent of the flaring rollers or disk, the holding frame therefor, and the spring clamp that

secures the holder within the casing body or shell, the stop shoulder feature being also shown in this view.

Figure 6 is a detail perspective view of 60 one of the spring clamps hereinafter referred to.

Figure 7 is a plan view of a shell or casing shaped for receiving an improved arrangement of tube expanding and end flaring means. 65

Figures 8 and 9 are detail sectional elevations that illustrate slightly different forms of mounting the expanding and flaring disk.

Figures 10, 11 and 12 are detail views of 70 further modifications hereinafter specifically mentioned.

In my present construction of tool for expanding and flaring tube ends, as in my patented expander before referred to, the 75 shell 3, in which the expanding and flaring elements are mounted, is made for an automatic feed and it has a number of (preferably three) radial straight slots 4 which are diagonally arranged with respect to the longitudinal axis of the tube, as is best shown in Figure 7.

The expanding rollers 2-2, in my present construction of tool, each have a central bearing 5 at each end for engaging the 85 bearing boxes 6-6 that fit into and are freely slidable in the opposite ends of the radial slots 4-4.

U-shaped spring clamps 91 are also provided, in my present invention, for engaging the shell 3 and holding the rollers 2-2 under tension and in the inwardly drawn position, the operation of the several parts mentioned being similar to the like parts in my patented tool before referred to. 90

My present invention in its essential features, differs from my patented tool in that a simple and effective means is provided for bending or flaring the end of the tube as it is being expanded by feeding the mandrel inwardly and as the shell is being turned, as it is being fed forwardly within the tube end. 100

Referring now more particularly to Figure 3 of the drawings, it will be noticed a 105 roller or disk 7 having a tapered or flared peripheral face 70 is mounted within the radial slot 4 adjacent the outer end of the roller 2.

The disk roller 7 has a minimum diameter 110 equal the diameter of the adjacent roller 2 and its peripheral edge is so beveled or flared

that it flatwise engages the mandrel in a plane parallel with the mandrel engaging portion of the said roller 2, it being apparent that the outer peripheral portion of the disk 5 flares outwardly, as at 70, with the beveled face beginning at the outermost end of the expanding roller 2.

By reason of providing a flaring disk 7 within the slot 4 and located at the outer- 10 most end of the roller 2, it follows that as the expanding roller about reaches the limit of the inward feed of the cage or shell 3, the disk roller 7 is caused to engage the outer edge of the open end of the tube and 15 as the cage is further fed into the tube, it bends up or flares the said end in the manner clearly understood from Figures 3 and 4 of the drawings.

In practice, a flaring disk need be, if de- 20 sired, provided for cooperating with but one of the expanding rollers and, when thus applied, the disk 7 has a sufficiently large aperture 72 to permit it to rotate freely around the center bearing of the adjacent 25 end of the roller 2, when arranged as in Figure 3.

If desired, the disk 7 may have an axial stud bearing 75 for engaging a socket 76 in the roller bearing box, as shown in Figure 30 12, and again a plain roller disk 7 may be used, as shown in Figure 11, in which the shell slot is shown peened where it receives the flaring disk roller 7 to prevent the said flaring roller or disk from falling in or out.

35 In my present construction of tube manipulating tool, those slots 4 in which only the expanding rollers are held have their inner end 30 formed with a radially extended stop shoulder 31, the purpose of said 40 shoulders 31 being to stop the further infeed of the cage after the flaring disk 7 shall have finished the operation of bending up or flaring the tube end at which time the rear edge of the disk 7 will be flush with the 45 outer edge of the tube and the shoulder 31 of the cage in position for engaging with the flared tube end to operate as a stop.

From the foregoing description taken in connection with the drawings, it is believed 50 the complete construction, the manner of operation and the advantages of my invention will be readily understood by those familiar with the use of tools or implements for shaping up the ends of boiler tubes.

55 To operate my present invention, the tool is placed in the boiler to a point where the

inner or smaller diameter of the disk 7 comes into contact with the end of the tube, the mandrel 1 is then placed between the expanding rollers 2 and the rotary motion 60 is started.

The self-feeding action on the mandrel and the rollers 2 forces the shell or roller holder further into the tube thereby causing the flaring roller or disk 7 to be drawn farther into the tube, also, it being apparent from the drawings that the flaring roller or disk 7 being tapered, in being forced further into the tube, while it revolves, flares or bends the end of the tube back, as shown. 70

The tube is then ready for beading. Providing the tube with expanding rollers and one or more flaring disks, as shown and described, it follows that the tube is expanded into the tube head and, under the same 75 operation, its outer end is flared ready for beading.

When the flaring roller 2 and the box 6 are arranged as in Figure 9, a pin 50 is connected with that end of the roller 2 adjacent 80 the flaring disk 7, passes through the aperture in the disk 7 and into a suitable socket in the adjacent box 6. The said pin connection 50 serves to hold the flaring disk and bearing box in close connection. 85

What I claim is:

In a tool of the character described, the combination with a tubular body having a plurality of longitudinally extending radial slots, an opposite pair of bearing boxes radially slidable within each of the slots, an expanding roller within each slot having end journals that rotatably engage their respective end bearing boxes, a tapering flaring disk rotatably mounted on the outer one of the expanding roller journals, the said disk being loosely mounted on the said journal, that end of the expanding roller engaging the disk being bevelled whereby to hold the disk at an angle with respect to said expanding roller and with its inner edge in a plane with the mandrel engaging surface of the expanding roller and its outer edge projected outwardly at an angle with respect to the tube engaging surface of the roller to 95 flare the outer edge of the tube, a tapering mandrel and tension devices engaging the tubular body and with opposite bearing boxes tending to normally move the expanding roller and the flaring disk against the 100 tube being worked. 105

THOMAS J. DIXON.
